INSTRUMENT CABINET

Willis J. Gray, Detroit, Mich.

Application January 7, 1950, Serial No. 7,082

Term of patent 14 years

(Cl. D83—1)

To all whom it may concern:

Be it known that I, Willis J. Gray, a citizen of the United States, residing at Detroit, county of Wayne and State of Michigan, have invented a new, original, and ornamental Design for an Instrument Cabinet, of which the following is a specification, reference being had to the accompanying drawing, forming a part thereof, in which:

Fig. 1 is a perspective view of one side of an instrument cabinet showing my new design; Fig. 2, a perspective view of the opposite side of the cabinet from that shown in Fig. 1; Fig. 3, a top plan view; Fig. 4, a front view in elevation; Fig. 5, a rear view in elevation; and Fig. 6, an end view in elevation.

I claim:

The ornamental design for an instrument cabinet, as shown.

WILLIS J. GRAY.
